United States Patent Office

Des. 190,809
Patented July 4, 1961

190,809

DOOR HOOD

Theodore J. Bottom, Kirkwood, Mo. (% Aluma Kraft
Mfg. Co., 1330 N. Rock Hill Road, St. Louis 17, Mo.)

Filed Jan. 4, 1960, Ser. No. 58,915

Term of patent 3½ years

(Cl. D21—6)

FIG. 1.

FIG. 3.

FIG. 2.

FIG. 1 is a top perspective view showing my new design for a door hood;

FIG. 2 is a bottom perspective view thereof as seen from the end opposite to that shown in FIG. 1, and

FIG. 3 is an enlarged view thereof, partly in cross section, as seen along line 3—3 of FIG. 1, illustrating the configuration of the roof panels and the interior of the side panels.

I claim:

The ornamental design for a door hood, substantially as shown and described.
